VALVE OPERATING MECHANISM

Herbert Harvey, Los Angeles, Calif., assignor to
United States Steel Corporation, a corporation
of New Jersey

Original application February 25, 1949, Serial No.
78,294. Divided and this application November
28, 1951, Serial No. 258,709

5 Claims. (Cl. 137—625)

1

This invention relates to an improved mechanism for operating pilot controlled slide valves in hydraulic circuits, such as fluid pressure actuated pumping units.

The present application is a division of my earlier application Serial No. 78,294, filed February 25, 1949, entitled "Fluid Pressure Actuated Pumping Unit."

An object of the present invention is to provide a fluid pressure mechanism for operating a slide valve, which mechanism is of simple construction and consumes a minimum of fluid in its own operation.

A further object is to provide a slide valve operating mechanism in the form of a cylinder and piston housed within a valve body, whereby the piston is motivated in one direction by pressures existing within this valve body, making it necessary to supply operating fluid from an external source to motivate the piston in the other direction only and eliminating stuffing boxes.

A further object is to provide a slide valve operating mechanism in the form of a piston and cylinder which loses fluid from a hydraulic circuit only when it moves the slide valve in one direction, thereby substantially reducing the volume of fluid which must be replenished to the circuit.

In accomplishing these and other objects of the invention, I have provided improved details of structure, a preferred form of which is shown in the accompanying drawings, in which:

Figure 1 is a schematic view of a hydraulic circuit like that embodied in the pumping unit shown and claimed in my aforesaid earlier application, but simplified by the omission of parts unnecessary for an understanding of the present invention;

Figure 2 is a vertical sectional view of the main valve and its operating mechanism embodying features of the present invention, the parts being in the downstroke position; and

Figure 3 is a vertical sectional view of these same parts taken on the line III—III of Figure 2, the parts being in the upstroke position.

Figure 1 shows a pumping unit which comprises a main cylinder 10, a single acting ram 12 reciprocable therein and connected to a sucker rod string 13, a motivating pump 14, a main four-way valve 15, a pilot valve 16, pressure

2

accumulator tanks 17 and 18 and a reservoir 19. Pump 14 is driven by any suitable drive means, not shown. To produce an upstroke of the ram, the pump 14 takes in hydraulic fluid from tank 18 via a pipe 20, main valve 15, and a pipe 21 and discharges this fluid via a pipe 22, main valve 15 and a pipe 23 to the lower end of cylinder 10. To produce a downstroke the main valve shifts, as hereinafter explained, so that the motivating pump takes in fluid from cylinder 10 via pipe 23, main valve 15 and pipe 21 and discharges this fluid via pipe 22, main valve 15 and pipe 20 to tank 18. Tanks 17 and 18 are in free communication with each other through an overflow connection 24. Tank 17 contains air under pressure, which is supplied from any suitable source not shown, and the pressure of which is applied to the fluid in tank 18 via the overflow connection. On the upstroke of the ram this pressure supercharges the motivating pump 14, and on the downstroke cushions the ram, which descends gravitationally.

Pilot valve 16 has a shiftable element which can be shifted back and forth by any suitable means at the ends of the ram strokes. Pipes 25, 26 and 27 are shown connected to the pilot valve for producing such shifting. In one position the pilot valve directs fluid under pressure from pipe 22, which is connected to the motivating pump discharge, via a pipe 28 to the operating mechanism for the main valve 15. In its other position the pilot valve relieves this operating mechanism via a pipe 29 which extends to the reservoir 19. A scavenger pump 30 returns fluid from reservoir 19 to tank 18 via pipes 31 and 32, the latter of which has a check valve 33. Since pilot valves which can function in this fashion are well known, no detailed disclosure is included in the present application, although reference can be made to my aforesaid application for a disclosure of one exemplary construction of a suitable pilot valve.

In accordance with the present invention, the main valve 15 includes a cylindrical body 34, the upper end of which carries the pilot valve 16. Two opposite side walls of body 34 have ports 35 and 36, to which the pipes 22 and 23 respectively are connected (Figure 3). Another side wall has a port 37 to which the pipe 20 is connected. The bottom has a port 38 to which the pipe 21 is

connected (Figure 2). The side wall opposite the port 37 has two ports 39 and 40 adjacent its upper and lower ends connected by a manifold 41 (Figure 2). A piston-type slide 42 is mounted for reciprocable movement in the body 34 and has an upper piston 43 and a lower piston 44. In the upper position of said slide illustrated in Figure 2, pipe 23 from the main cylinder 10 communicates with pipe 21 to the pump intake and pipe 22 from the pump discharge communicates with pipe 20 to the pressure accumulator to effect a downstroke of the ram 12. In the lower position illustrated in Figure 3, pipe 20 from the pressure accumulator communicates via the manifold 41 with pipe 21 to the pump intake and pipe 22 from the pump discharge communicates with pipe 23 to the main cylinder 10 to effect an upstroke. The ports 39 and 40 and manifold 41 at all times furnish free communication between the upper and lower end portions of the valve body 34, and these ends in both positions of slide 42 are subjected to a positive pressure, derived either from the main cylinder 10 on the downstroke or from the tank 18 on the upstroke.

The operating mechanism of the present invention includes a cylinder 45 housed within the upper portion of the valve body 34, being illustrated as integral with the top wall thereof. The upper end of the valve slide 42 carries a piston rod 46 and a piston 47, the latter being reciprocable in cylinder 45. The bottom or inner wall of said cylinder contains an opening 48 of somewhat larger diameter than piston rod 46. Consequently the pressure in the upper part of the valve body is at all times applied to the bottom or inner side of piston 47 and tends to push this piston and the valve slide 42 upwardly to the downstroke position shown in Figure 2.

The pilot valve 16 has ports 49 which communicate with the upper end of cylinder 45. When the shiftable element of the pilot valve is in the downstroke position, ports 49 are relieved to pipe 29 and reservoir 19. Consequently pressure on the bottom of piston 47 moves this piston and the valve slide upwardly. When the shiftable element of the pilot valve is in the upstroke position, ports 49 receive pressure from the discharge of the motivating pump 14 via pipe 28. This pressure is greater than that within the valve body; consequently this pressure forces the piston 47 and the valve slide downwardly. It is seen that the pressures on the top of piston 43 and on the bottom of piston 44 substantially balance each other, but the small differential, which is due to the greater effective area of the latter, merely assists the pressure applied to the bottom of piston 47.

To cushion the movement of piston 47 and valve slide 42, the piston rod 46 carries lower and upper collars 50 and 50a which are adapted to fit rather closely within the opening 48, although the fit is not fluid-tight. Near the ends of the stroke of piston 47 one of these collars enters the opening 48 and produces a dash-pot effect, which decelerates and cushions the movement. The lower end of cylinder 45 can have a depending annular flange 51 and piston rod 46 can have an additional collar 52 which fits within said flange to furnish additional cushioning on upward movement of the piston.

From the foregoing description it is seen that the main valve slide 42 moves upwardly under the influence of pressure which always exists within the main valve body 34. It is necessary to supply pressure from an outside source only to move

the main valve slide downwardly. It is necessary to relieve the main valve operating mechanism only as the slide moves upwardly. Thus only the upward movement loses fluid from the main circuit to the reservoir 19, and the scavenger pump 30 needs to return a minimum of fluid to the tank 18. At the same time the need for stuffing box connections to the main valve and its operating mechanism is completely eliminated.

While I have shown and described only a single embodiment of the invention, it is apparent that modifications may arise. Therefore, I do not wish to be limited to the disclosure set forth but only by the scope of the appended claims.

I claim:

1. The combination with a four-way slide valve which includes a cylindrical body having ports in its walls, a slide reciprocable in said body and having two positions providing different communication among said ports, and means furnishing free communication between the opposite end portions of said body, said end portions being adapted to be subjected to a positive pressure in both positions of said slide, of an operating mechanism comprising a cylinder housed within one end portion of said body and fixed to the end wall thereof, a piston reciprocable in said cylinder, a piston rod attached to said piston and to said slide, said cylinder having an inner end wall which has a passage larger than the cross section of said piston rod and through which said piston rod extends, said passage furnishing free communication for subjecting the inner face of said piston to the pressure within the end portions of said body, and means for applying pressure to and relieving said cylinder on the other side of said piston.

2. The combination with a four-way slide valve which includes a cylindrical body having at least three ports in its side walls and a port in one end wall, a slide reciprocable in said body and having two positions providing different communication among said ports, and ports and a manifold furnishing free communication between the opposite end portions of said body, said end portions being adapted to be subjected to a positive pressure in both positions of said slide, of an operating mechanism comprising a cylinder housed within the end portion of said body opposite the end wall which has the port and fixed to the end wall, a piston reciprocable in said cylinder, a piston rod attached to said piston and to said slide, said cylinder having an inner end wall which has a passage larger than the cross section of said piston rod and through which said piston rod extends, said passage furnishing free communication for subjecting the inner face of said piston to the pressure within the end portions of said body and means fixed to the end of said body for applying pressure to and relieving said cylinder on the other side of said piston.

3. A combination as defined in claim 2 in which the operating means also comprises means for cushioning the movement of said piston near the ends of its strokes.

4. A combination as defined in claim 2 in which said piston rod has spaced apart collars adjacent said piston and said slide, which collars are adapted to be received in the passage in the inner end wall of said cylinder for cushioning movement of said piston near the ends of its strokes.

5. The combination with a four-way slide valve which includes a cylindrical body having ports in its walls, a slide reciprocable in said body and having two positions providing different com-

munication among said ports, and means furnishing free communication between opposite end portions of said body, of an operating mechanism comprising a cylinder housed within one end portion of said body and fixed to the end wall thereof, a piston reciprocable in said cylinder, a piston rod affixed at one of its ends to said piston and at its other end to said slide so that movement of said piston in either direction moves said slide correspondingly, the face of said piston which is directed toward said slide being always exposed to the pressure existing within the end portions of said body, means for applying a posi-

tive pressure to said end portions in both positions of said slide, and means for periodically applying pressure to and relieving said cylinder on the opposite face of said piston.

HERBERT HARVEY.
